UNITED STATES PATENT OFFICE

168,100

PORTABLE DRILL UNIT

Eugene J. Majewski, Chicago, Ill., assignor to Portable Electric Tools, Inc., Chicago, Ill., a corporation of Illinois

Application June 24, 1952, Serial No. 20,328

Term of patent 14 years

(Cl. D54—14)

To all whom it may concern:

Be it known that I, Eugene J. Majewski, a citizen of the United States, residing at Chicago, in the county of Cook and State of Illinois, have invented a new, original, and ornamental Design for a Portable Drill Unit, of which the following is a specification, reference being made to the accompanying drawings, forming a part hereof.

In the drawings:

Fig. 1 is front perspective view of a portable drill unit showing my new design;
Fig. 2 is a front end elevational;
Fig. 3 is a top plan view thereof;
Fig. 4 is a side elevational view; and
Fig. 5 is a rear end elevational view thereof,

I claim:

The ornamental design for a portable drill unit, substantially as shown.

EUGENE J. MAJEWSKI.
